SELF-CLEANING SHOWER HEAD

George E. Hansen, Chicago, Ill., assignor to Crane
Co., Chicago, Ill., a corporation of Illinois

Application January 16, 1951, Serial No. 206,230

3 Claims. (Cl. 299—59)

1

This invention relates to a shower head, and, more especially, it pertains to a shower head of a self-cleaning type for shower baths or the like.

It has long been a problem in relation to the operation of shower heads to overcome the objectionable result of line accumulations of foreign deposits in the flow passages of the shower head, since sediment in the water or hard water frequently has led to substantial clogging of the flow passages and thus presented a serious problem in shower head operation.

Presently known self-cleaning shower heads include a spring action type of deflector plate or disc.

It is an important object of this invention to provide a shower head which is relatively simple and self-cleaning, and thereby eliminates clogging of the flow passages.

Another important object of this invention is to provide a shower head which does not permit water to drip after closing off the water supply valve.

Other objects and advantages will become more readily apparent upon proceeding with the following description read in light of the accompanying drawings, in which,

Fig. 1 is a fragmentary sectional assembly view of a preferred embodiment of this invention.

Fig. 2 is a fragmentary sectional view of the same embodiment shown in Fig. 1, but in a different operational position.

Fig. 3 is an end exterior view of the embodiment shown in Figs. 1 and 2.

Fig. 4 is a fragmentary sectional assembly view of a modification of the embodiment shown in Fig. 1.

Fig. 5 is a fragmentary sectional assembly view of a further modification of the embodiment shown in Fig. 1.

Fig. 6 is an end exterior view of the embodiment shown in Fig. 5.

Similar reference numerals refer to similar parts throughout the several views.

Proceeding with the description and as shown in Fig. 1, the shower head 10 is indicated as being in a body portion 11 is shown in a fragmentary sectional view to comprise a central liquid passageway 12 and a substantially spherically formed exterior head section 13. Means for connecting the shower head 10 to a supply conduit (not shown) can be of the conventional threaded type within the rearward body portion, but these connecting means are not deemed necessary to show in these drawings.

2

A shower head casing 14 is mounted over the body head section 13 by receiving the latter within a central casing opening 16 which is slightly smaller than the largest transverse dimension of the head section 13. This assembly is made by the usual method of passing the body portion 11 through the casing 14 to a position in which the body head section 13 contacts the upper annular wall of the reduced opening of casing passageway 16. Thus, it should be apparent that the body 11 and casing 14 are swivelably arranged in the usual manner to provide for directional control of the shower spray.

It should also be noted that the body flow passage 12 communicates with the casing flow passage 16 which extends axially through the casing 14. Thus, water is conducted through the shower head 10 by means of the flow passages, past the other elements to be hereinafter described, and is discharged out the casing outlet opening 15.

An internal portion of casing 14 is preferably threaded about its flow passage to receive there-within a perforated baffle plate 17 having flow passage means therewithin, such as a plurality of apertures 18, annularly located in the plate 17, and an axial central opening 19. A resilient member, such as the coil spring 21, is preferably disposed within the casing 14 to abut the upper surface of the plate 17 and to extend therefrom to an annular packing material 22 which surrounds a portion of the casing spherical head section 13 and preferably has a conforming arcuately formed abutting surface. Thus, a liquid tight swivel joint is obtained between the body 11 and the casing 14. A bearing washer 23 is provided between the coil spring 21 and the packing material 22 to insure suitable spring loading of the latter against the head section 13.

Disposed within the casing 14 below the plate 17 is a liquid deflector means, such as a circularly shaped flow disc 26, which has an upwardly extending shank portion 27 slidably received within the baffle plate central opening 19.

The foregoing structure is conventional and the description hereinafter following applies to the novel feature with which this invention is primarily concerned. An annular steel ring 28 is press-fitted or otherwise suitably connected to the upper surface of flow disc 26. Aligned with ring 28 is an annularly shaped permanent magnet 29 press-fitted or otherwise secured to the casing 14 to be partially exposed therefrom. Thus, as shown in Fig. 1, the magnet 29 normally attracts the ring 28 so as to thereby draw the disc

26 upwardly within the casing 14, disc shank 27 being free to move slidably within the plate spring 19.

Thus, when the water supply is turned on, water pressure passes within the shower head 10 through the passages 12 and 16 and the apertures 18 to where it strikes against the flow disc 26 to force the latter downwardly and away from the magnet 29 to an open position as shown in Fig. 2. A washer 31 secured to the top of the shank 27 by a screw 32, extends beyond the transverse limits of the shank to abut the plate 11 in the downward movement of the disc 26 and the connected shank 27. Thus, the disc 26 is secured within the casing 14 against the water pressure therewithin.

In the operating position shown in Fig. 2, water is thus permitted to flow around the disc 26 which is preferably provided around a peripheral portion 33 with serrations or notches 34, as better shown in Fig. 3. The relation between the disc periphery 33 and an adjacent inner annular casing face portion 36 is such that water is permitted to flow out around the disc and through the notches 34 to form the desired shower spray. Obviously, the casing face 36 could be provided with the serrations, with the disc either being serrated or made plain, as desired.

Upon the cessation of flow through the shower head 10, the magnet 29 again draws the disc 26 upward to the closed position shown in Fig. 1. The latter motion of the disc effects a cleaning of the shower head around the casing outlet 15 as the operating relation of the disc 26 to the casing face 36 is changed and thereby aids in loosening any accumulations or deposits clinging thereto.

Also, it should be noted that in the position shown in Fig. 1, water dripping is prevented by virtue of rapid evacuation of water from the shower head and by the ring 28 tightly abutting the magnet 29 to form a liquid seal therebetween. Thus, hard water precipitates cannot form on the walls of the casing outlet 15 nor on the disc 26 which form the outlet passages.

A modification of the above described invention is shown in Fig. 4 in the operating position where a casing 41 is connected to the body 11 as previously described. Body flow passage 12 communicates with a flow passage 42 of the casing 41, as shown. A baffle plate 43 is threadedly mounted within the casing to support a coil spring 44 which maintains a packing material 46 in liquid tight relation against the body 11 as described in connection with Fig. 1.

A plurality of apertures 47 annularly spaced in plate 43 permit liquid flow therethrough and into the casing outlet portion 48. Preferably fixedly mounted on the plate 43 is a spindle 49 which depends therefrom to support a flange end 51 in the outlet 48 of the casing, thereby providing a predetermined annular outlet space between the outer periphery of the flange 51 and the wall of the outlet 48. The periphery of the flange 51 is preferably provided with notches 52 which effect the spray discharge of the water, similar to that structure described in connection with Figs. 1, 2, and 3 as the end view of Fig. 4 is similar to the view shown in Fig. 3.

Here similarly, a permanent magnet 53 is press-fitted or otherwise positioned within the casing 41 below the plate 43. An inverted cup-like steel member 54 is slidably mounted on the spindle 49 to reciprocably move thereon in response to the water pressure within the casing as described in

connection with Fig. 1. A plurality of flow apertures 56 are annularly provided in the member 54 to permit water flow therethrough.

Thus, the member 54 is alternately actuated to move within the casing 43 by either the water pressure or the magnet, and thereby likewise providing for self-cleaning of the shower head as described in connection with Fig. 1.

A further modification of this invention is shown in Figs. 5 and 6. In Fig. 5, a fragmentary sectional assembly view of a shower casing 59 is shown, being provided with a flow passage 61. An annular magnet 62 is press-fitted or otherwise secured within the casing around the flow passage 61. An end plate 63 is preferably threadedly engaged into the liquid outlet end of the casing 59 and is provided with a plurality of annularly spaced liquid outlet apertures 64 which are preferably of a polygonal shape, such as hexagonal, as shown in Fig. 6.

A plurality of steel balls 66, one for each of the outlet apertures 64, are disposed within the casing 59 above the end plate 63. Thus, in the operational position shown, the spheres 66 seat imperfectly in the polygonal outlet apertures, thereby to provide outlet passages 67 at the corners of the hexagonally shaped apertures, as shown in Fig. 6.

Upon cessation of water flow through the shower head, the spheres 66 are drawn upwardly to the magnet 62, and thereby effect the self-cleaning of the outlets as previously described in connection with Fig. 1.

Means for guiding the spheres 66 in their upward and downward travel is shown to consist of a cylindrically shaped brass insert 68 preferably disposed on the inner periphery of the casing 59, and a smaller brass insert 69 is disposed within the insert 68 to guide the balls therebetween. Each insert is preferably provided with axially disposed projections 71 which guide the spheres against transverse movement in the casing 59. Thus, each sphere is separately guided in axial movement within the casing. To secure the inserts in position, connecting struts 70 are preferably provided between the two inserts.

Thus it will be apparent that a relatively simple, efficient and economical structure has been provided for a shower head, and, although this invention has been described in specific forms, it is susceptible to numerous changes, and it should, therefore, be limited only by the spirit of this invention and the scope of the appended claims.

I claim:

1. In a shower head construction, the combination comprising a casing having an inlet and outlet and means within said outlet adapted to form an annular outlet space in cooperation with the inner wall of said casing including an inverted cup-shaped member positioned within said casing for reciprocal movement, said member having a depending skirt interposable between said means within said outlet and the inner wall of said casing in the lowermost position of said cup-shaped member during substantial fluid flow through said casing to restrict said annular outlet space for the formation of a shower spray, said cup-shaped member being apertured through the top to permit fluid flow within said member, a magnet within said casing mounted above said cup-shaped member for displacement of the latter from its lowermost shower spray forming position when substantial fluid flow through the casing has stopped, said magnet forming an abutment limiting the upward movement of said cup-shaped

member, said cup shaped member serving as a keeper for the magnet when in the uppermost abutting position, said apertures in said cup-shaped member being positioned so as to be open and effective in the passage of fluid from the inlet to the outlet of said casing for all positions of said reciprocal cup-shaped member.

2. In a showerhead construction, the combination comprising a casing having a fluid passage therethrough and fixed apertured means extending across said fluid passage, axial stem means secured to said apertured means, said stem means having a disc-like portion at the lower end thereof which is uniformly spaced from a portion of said casing to form an annular outlet opening, an inverted cup-shaped member mounted on said stem for reciprocal movement, said cup-shaped member having a depending skirt portion interposable between said lower disc-like portion and said outlet forming portion of the casing in the lowermost position of said cup-shaped member during substantial fluid flow through said casing to restrict said annular outlet for the formation of a shower spray, said cup shaped member being apertured through the top to permit fluid flow within said member, an annular magnet mounted on said casing, said magnet being positioned above said cup-shaped member for displacement of the latter from its lowermost shower spray forming position when substantial fluid flow through the casing has stopped, said magnet having an exposed surface for annular abutting contact with said cup-shaped member in the uppermost position thereof, said cup-shaped member serving as a keeper for the magnet when in the uppermost abutting position, said apertures in said member being positioned inwardly towards the center of said abutment with said magnet and being in communication with the apertures in said apertured means of the casing and effective for fluid passage through said casing for all positions of said reciprocal cup-shaped member.

3. In a showerhead construction, the combination comprising a casing having a fluid passage therethrough and fixed apertured means extending across said fluid passage, axial stem means secured to said apertured means, said stem means having a disc-like portion at the lower end thereof which is serrated around its outer periphery, said serrated periphery being uniformly spaced from the inner wall of said casing to form an annular outlet opening, an inverted cup-shaped member mounted on said stem for reciprocal movement, said cup-shaped member having a depending skirt portion interposable between said

5 lower disc-like portion and the inner wall of said casing in the lowermost position of said cup-shaped member during substantial fluid flow through said casing to restrict said annular outlet for the formation of the shower spray, said cup-shaped member being apertured through the top to permit fluid flow within said member for spray discharge between the serration of said disc-like portion and the inner surface of said skirt when 10 the cup-shaped member is in the lowermost spray forming position, the outer surface of said skirt being imperforate and cylindrical for contact along the entire surface thereof with the inside of said casing for guidance and positioning and 15 relatively close fit relation therewith to substantially eliminate the passage of fluid around the outside of said cup-shaped member, an annular magnet mounted on the inside of said casing, said magnet being positioned above said cup-shaped member for displacement of the latter from its lowermost shower spray forming position when substantial fluid flow through the casing has stopped, said magnet having an exposed surface for annular abutting contact with the top of said 20 cup-shaped member in the uppermost position thereof, said cup-shaped member serving as a keeper for the magnet when in the uppermost abutting position, said apertures in said member being inwardly of said abutment with said magnet 25 for constant communication with the apertures in said apertured means of the casing for fluid passage through said casing for all positions of said reciprocal cup-shaped member.
